UNITED STATES PATENT OFFICE.

LESTER B. LAZIER, OF BUFFALO, NEW YORK.

SUSPENDER.

Application filed April 16, 1925. Serial No. 23,562.

To all whom it may concern:

Be it known that I, LESTER B. LAZIER, a citizen of the United States, residing at Buffalo, in the county of Erie and State of New York, have invented certain new and useful Improvements in a Suspender, of which the following is a specification.

This invention relates to improvements in suspenders, and particularly suspenders adapted for use by men for supporting the trousers.

An object of the invention resides in providing a suspender formed of a single suspender element having the central portion formed of a curved section for application around the neck and over the shoulders of a wearer with the opposite end portions carrying adjustable elastic sections having suitable fasteners at the ends for removably receiving suspender loops adapted for attachment to the trousers, and for extension through suitable openings in the shirt so that the suspender may be worn under the shirt.

25 A further object of the invention is to provide a suspender of the above character which will be comfortable to the wearer and provide a pair of supporting points for the trousers at opposite sides thereof, and which 30 will not place an undue strain in supporting the trousers in the various positions of the wearer.

A still further object of the invention resides in providing a special form of suspender loop having a loop formed in the central portion and retained therein by a knot, said knot serving to prevent the withdrawal of the loop through the buttonhole formed in the shirt when the loop is removed from the button on the trousers, while the ends are secured together to form a substantially large loop portion for receiving the fastening means on the end of the elastic section to which it is secured.

45 The invention comprehends other objects and improvements in the details of construction and formation of the parts which are more particularly pointed out in the following description and claims directed to 50 the preferred form of the invention, it being understood however that various changes may be made in the shape, size and arrangement of the parts without departing from the spirit and scope of the invention as 55 set forth herein.

In the drawing, forming part of this application—

Figure 1 illustrates the manner of applying the invention so that the suspender will be concealed beneath the shirt, and only the 60 button loop shown on the outside thereof.

Figure 2 is an enlarged view showing the suspender laid out to illustrate the shape and arrangement together with the detailed construction of the several parts. 65

Figure 3 is a detail perspective view of the suspender loop showing the manner in which it is inserted through a button hole in the shirt when the suspender is first placed in use. 70

Referring more particularly to Figure 2, the central portion 1 of the suspender which is made to fit over the shoulders and around the neck as illustrated in Figure 1 is composed of a pair of fabric sections of a suitable soft fabric sewed together along the edges as indicated at 2, which sections are cut according to a curved pattern in order that the side indicated by the numeral 3 will be substantially shorter than that indicated at 4, so that the curved fabric sections will conveniently and comfortably fit the back of the neck of the wearer as illustrated in Figure 1 and pass over the shoulders so that this central section will not 85 wrinkle or be uncomfortable when being worn in the position as illustrated in Figure 1. Link portions of usual construction indicated at 5 are mounted in the end portions of the sections 1 and to which are connected 90 the adjustable elastic sections 6. A fastener 7 is connected to one end of each elastic section while the opposite ends are loosely passed through the members 8 and secured at their ends to the links 5 by passing the ends through the links and stitching them to the adjacent end portions of the section. This permits the fastener 7 to be adjusted for lengthening or shortening the portions of the sections looped through 95 members 8 so that the length of the suspender may be conveniently and readily adjusted. 100

Each elastic section 6 carries at its free end, opposite the end of the section 1, suitable end members 8 which carry the cast offs 9 having the separable fasteners 10 and which hold the suspender loops 11. 105

These suspender loops are formed of a single length of cord adapted for the pur- 110

pose which is shown particularly in Figure 3. The central portion of the cord is formed into a loop as indicated at 12 which is retained in form by the knot 13, while the free 5 ends extend and are secured in parallel relation by the binding 14 of any suitable character. The free ends when bound by the binding 14 form an additional loop which is adapted to be received by the cast offs 9.

10 The suspenders are worn under the shirt so as to be concealed in the manner as illustrated in Figure 1, and when being applied, the suspender loops 11 are removed from the cast offs 9 while the central section with 15 the elastic sections are applied around the neck with the ends extending forward over the shoulders and down the front of the body and substantially at the side portions thereof. The suspender loops 11 then 20 have the parallel ends secured as shown at 14 extended through the button holes 15 which have been previously formed in the shirt, which are then received and secured by the cast offs 9 to the ends of the elastic 25 sections in the manner as illustrated in Figure 2. In this connection it will be noted that the knot 13 serves to prevent the loop 12 from being drawn inwardly through the button holes to the inside of the shirt which 30 would cause considerable inconvenience in the use and application of the suspenders to the trousers. In this way the loops are always available so that they may be readily applied to the buttons on the inside of the 35 waist band of the trousers as illustrated in Figure 1 to effectively support the same.

As the ends of the suspender structure are secured at the sides of the trousers and substantially under the arms, it will be seen 40 that the twisting movements of the body will not be exerted in the majority of movements to exert a pull on the elastic sections, as the bending movements will normally be

laterally with respect to the directions of the suspenders. It will therefore be seen 45 that a comfortable and simple suspender structure is provided which may be worn under the shirt and concealed from view, and wherein the portion which fits the neck is tailored to fit the curvature of the body at 50 this portion in order to provide the most comfortable fit.

Having thus described the invention, what I claim as new and desire to secure by Letters Patent is:—

55

1. A suspender, comprising a central curved section, a pair of adjustable elastic sections secured to the ends of the curved section, cast offs on the ends of the elastic sections, and suspender loops removably 60 held by said cast offs having knots tied in their central portions, said suspender loops being adapted for attachment to the trousers and for extension through button holes formed in the shirt in order that the suspender may be concealed under the shirt, said knots preventing the withdrawal of the loops through the shirt.

2. A suspender, comprising a single suspender member having a curved central portion, and adjustable elastic sections at the ends of said central portion carrying cast offs, and suspender loops adapted for removable connection with said cast offs and formed of cord members having loops provided in the central portion, said cord members being provided with a knot for maintaining the loops in the central portions, the end portions extending in parallel relation, and securing means for binding the end portions in rigid connection, said knot preventing the withdrawal of the loops in one direction through buttonholes formed in a shirt.

In testimony whereof I affix my signature.
LESTER B. LAZIER.
